UNITED STATES PATENT OFFICE.

FRANK B. MOREHOUSE AND FRANK HAASE, OF SAN FRANCISCO, CALIFORNIA, ASSIGNEES, BY DIRECT AND MESNE ASSIGNMENTS, TO TRAYWAY MFG. CO., A CORPORATION OF CALIFORNIA.

WASHING MACHINE.

Application filed October 10, 1923. Serial No. 667,635.

The invention relates to a portable washing machine adapted to be used to wash clothes in stationary laundry trays.

An object of the invention is to provide a simple and efficient washing machine for washing clothes in laundry trays.

Another object of the invention is to provide a washing machine which may be readily attached to and removed from the laundry tray.

Another object of the invention is to provide a washing machine for use in connection with a laundry tray in which the driving bar for the impeller, which is located in the tray, may be readily removed, to facilitate the removal of laundry from the tray.

Another object of the invention is to provide a completely enclosed power driven washing machine, for use in connection with laundry trays, in which the liability of lubricants from the machine, coming into contact with the laundry, is reduced to a minimum.

The invention possesses other advantageous features, some of which, with the foregoing, will be set forth at length in the following description, where we shall outline in full, that form of the invention which we have selected for illustration in the drawings accompanying and forming part of the present specification. In said drawings we have shown one form of washing machine embodying our invention, but it is to be understood, that we do not limit ourselves to such form, since the invention, as set forth in the claims, may be embodied in a plurality of forms.

Referring to said drawings:

Figure 1 is an end elevation of the washing machine mounted on a stationary laundry tray, a portion of the tray being broken away to show portions of the machine.

Figure 2 is a top or plan view of the impeller.

Figure 3 is a side elevation of the washing machine mounted on a laundry tray, portions of the machine being broken away and being shown in section to illustrate the construction.

Figure 4 is a detail showing the means for reversing the direction of rotation of the wringer roll.

Figure 5 is a vertical section of the ma-

chine showing the gearing for driving the wringer rolls and impeller.

Figure 6 is an underneath view of the arm of the machine with the lower plate removed, showing the drive for the impeller.

Figure 7 is a cross section of the machine taken on the line 7—7 Figure 3.

Figure 8 is a perspective view of a portion of the arm and casing in detached relation.

The machine of our invention is adapted to set on and be clamped to a stationary laundry tray for the purpose of washing clothes in the tray. In the drawings we have shown the machine mounted on a two compartment tray and positioned over the central transverse wall of the tray. The machine is provided with an arm which extends into one of the trays and this arm carries the impeller driving mechanism, for driving the impeller which is arranged in one of the trays. The impeller is given an oscillating movement which causes agitation and swirling of the water and clothes in the tray, thereby effectively washing the clothes.

The machine comprises a frame having end plates 2 and 3, which are suitably fastened together by the transverse bolts 4 extending through the end plates. The end plate 2 rests on the front wall 5 of the laundry tray and is provided with lateral extensions 6 which also rest on the front wall.

These extensions are provided with clamps 7 for securing the machine to the laundry tray. The clamp comprises a yoke pivoted to the extension so that the clamp may readily adjust itself to front walls of varying inclination. One face of the yoke rests against the outer face of the front wall and the other arm of the yoke is provided with a screw 8 which is turned to secure the clamp to the front wall. The driving motor 9 is supported on the end plate 3 of the frame. In practice we remove the standard end plate from the motor and secure the motor shell to the end plate 3, which is formed to receive the motor shell. The motor is enclosed within a housing 13, which is preferably cylindrical in form and which sets on shoulders on the end plates 2 and 3.

This housing encloses the motor so that it cannot become wet and so that there is no possibility of the person using the machine, coming in contact with the motor. The end

plates are preferably provided with apertures to permit air to circulate through the housing 13, to keep the motor cool.

The wringer rolls are arranged above the 5 housing and the water expressed from the laundry by the wringer flows over the adjustable drain board 10, which may be inclined in either direction, to divert the water into either laundry tray. From the drain 10 board the water flows over the housing 13, which is provided on its under side, at opposite sides of the transverse wall of the laundry tray, with ribs 20 which deflect the water flowing over the housing into the 15 desired tray and prevent it from flowing over the transverse wall into the other tray.

Formed integral with the end plate 3, is a casing 14 into which the motor shaft 15 extends. The motor shaft is provided on its 20 end with a worm 16 which meshes with a worm wheel 17, secured to a vertical shaft 18, journaled in the casing. The casing 14 is preferably cylindrical in form, and the shaft 18 is preferably concentric with the 25 casing. Detachably secured to the lower end of the casing 14, by a suitable joint, such as the breech lock 19, is an outwardly extending member preferably in the form of a hollow cantilever arm 21 which overlies the 30 interior of the washing tray. The arm 21 is horizontally disposed and positions the driving bar of the washing mechanism. The arm 21 is provided on its upper and lower surfaces with hollow bosses 22 and 23 which 35 form bearings for the vertically disposed hollow shaft 24 to which the gear 25 is secured. The hollow shaft 24 may be formed integral with the gear 25. The hollow shaft 24 is provided with a non-circular bore, 40 preferably rectangular, through which extends the driving bar 26, which drives the impeller 27, which is disposed in the laundry tray. The impeller 27 is provided with a non-circular socket 28 corresponding to the 45 bore in the shaft 24 and the driving bar 26 is preferably loosely disposed in said socket and hollow shaft, so that the driving bar may be readily removed, to facilitate the removal of the laundry from the tray.

50 Since laundry trays are of different widths and have front walls of different inclinations, the relation of the center of the bottom of a tray and the intersection of the front and transverse walls vary in different 55 trays, means are provided for adjusting the position of the impeller so that it may be disposed at the center of the bottom of the tray. The arm 21 is movable in a horizontal plane about the joint 19 to properly position the impeller and is held in adjusted 60 position by suitable means, such as the setscrew 64 which locks the arm in position. Due to the slideable fit of the bar 26 in the hollow shaft 24, the machine is half-adjusting to trays of different depth. This free

vertical movement of the impeller is also advantageous to prevent strains in the apparatus due to the collection of articles of laundry under the impeller. In the event that an article finds its way under the impeller, the impeller is merely lifted vertically, so that no deleterious results are produced.

The hollow shaft 24, produces rotation of the driving bar and the driving bar produces rotation of the impeller, but the driving bar is slidably fitted into the hollow shaft and impeller, and by grasping the upper end of the driving bar, which projects above the boss 22, the driving bar may be readily removed. The impeller is provided with vanes which produce an agitation of the water and laundry in the tray and is provided on its under side with a pad 30 which rests against the bottom of the tray.

Means are provided for producing an oscillating rotary movement of the impeller 27. Disposed within the hollow arm 21 and engaging the gear 25 is a rack bar 31 which is given a reciprocating movement by the crank 32 which is formed on the lower end of the vertical shaft 18. The shaft 18 is rotated by the motor 9, causing reciprocation of the rack 31 and oscillation of the gear 25, and the gear 25 is preferably of such diameter that reciprocation of the rack causes oscillation of the gear through an arc of approximately 180°. The rack is held in mesh with the gear 25 by a roller 33 seated in a pocket formed in the arm. The arm is also provided with a lubricant chamber 34 which communicates with the bearings of the hollow shaft 24 by the passages 35. Packing rings 36, in the hollow bosses, prevent the lubricant from working out of the bearings. The hollow arm is closed on the under side by a plate 37; the lower surface of which is depressed below the marginal edge of the plate, forming trays or sumps for receiving and holding any lubricant which finds its way into the hollow arm, thus preventing any lubricant from leaking from the arm and coming into contact with the laundry.

Disposed above the motor housing 13 are a pair of wringer rolls 41 and 42, the axes of which are parallel to the axis of the housing 13. The wringer rolls are journaled in the end plates of the machine and means are provided for rotating the rolls in either direction or for holding them inoperative. Secured to the shaft 18 above the gear 17, is a gear 43 which meshes with a gear 44 which is secured to or formed integral with the hollow shaft 45. The hollow shaft 45 is journaled in the casing 46 which is mounted on the casing 14, and arranged within and splined to the hollow shaft is a vertical shaft 47 which is capable of vertical movement, while maintaining driving relations with the

- shaft 45. The shaft 47 is extended down into a socket in the casing 14 and a spring 48 is interposed between the end of the shaft and the bottom of the socket and tends to move the shaft 47 upward to its highest position. The vertical position of the shaft 47 is determined by the cam lever 49, pivoted to the upper end of the casing 46 and engaging the upper end of the shaft 47. By moving the lever 49, the shaft 47 may be positioned in its upper position, lower position, or intermediate position. Loosely mounted on the shaft 47 are two bevel gears 51 and 52 which are in mesh with the bevel gear 53 which is secured to the drive shaft 54 of the wringer rolls 41 and 42. Either of the gears 51 and 52 may be rotatably secured to the shaft 47 so that it rotates therewith or both gears 51 and 52 may remain idle. Each bevel gear 51 and 52 is provided on its surface which lies adjacent the axis of the shaft 54 with a notch 56 which is adapted to be engaged by a pin carried by the shaft 47 to cause rotation of the engaged gear. The pin 57 is adapted to engage the gear 51 when the shaft 47 is raised to its uppermost position, and the pin 58 is adapted to engage the gear 52 when the shaft is depressed to its lowermost position. Thus when the shaft 47 is raised, the wringer rolls are rotated in one direction and when the shaft 47 is depressed to its full extent, the wringer rolls are rotated in the reverse direction. The distance between the gears 51 and 52 is such that the pins 57 and 58 may be positioned between the gears and out of contact with both of them, thus interrupting the driving connection between the shaft 47 and the shaft 54; so that the wringer rolls remain stationary.
- 40 The machine is further secured to the laundry tray by the back clamp 61 which engages the transverse wall of the laundry trays. Formed on the casing 14 is a lug 62 to which the clamp 61 is pivoted and a screw 45 passing through the clamp serves to clamp the transverse wall between the clamp and the inner end of the arm 21. The machine is thus secured to the trays at three spaced points, so that it is firmly held in 50 position.
- We claim:
1. In a washing machine, a casing, a hollow arm extending horizontally from said casing, a hollow vertical shaft journaled in said arm adjacent its outer end, a gear on said shaft, a rack enclosed in said arm and engaging said gear, a motor adjacent said casing and above said arm, drive means depending in said casing and adapted to cooperatively connect said motor and rack, and impeller means connected to said hollow vertical shaft.
  2. In a washing machine, a casing, an arm extending from and having one of its ends supported by said casing, a hollow vertical
- shaft journaled in said arm, said shaft having a non-circular bore, means for oscillating said shaft, an impeller having a non-circular bore and a rod slidably in said bores and connecting the shaft and the impeller. 70
3. In a washing machine, a vertical shaft having a non-circular bore therein, means for oscillating said shaft, an impeller having a non-circular bore therein disposed vertically below said shaft and a bar fitting in said bores and normally slidable vertically therein, so that the bar may be readily removed from the impeller and the shaft by lifting the same. 75
4. In a washing machine, a frame, a hollow elongated arm extending outwardly from said frame, a hollow casing supported by the frame adjacent said arm, a vertical hollow shaft journaled in said arm at a point remote from the frame, a depending shaft disposed in said casing, a horizontal shaft above said arm and cooperatively connected to drive said depending shaft, and means disposed in said hollow arm for driving said hollow shaft from said depending shaft. 80
5. In a washing machine, a casing, a hollow arm extending horizontally from said casing, a vertically disposed hollow shaft journaled in said arm adjacent its outer end, said shaft having a non-circular bore opening at the top and bottom of the arm, means in said arm for oscillating said shaft, an impeller having a vertical non-circular bore arranged below said shaft and a bar fitting said bores and slidably removable vertically therefrom. 95
6. In a washing machine adapted to be mounted on a stationary laundry tray, a frame, washing means carried by said frame, extensions on said frame overlying the front wall of the tray and clamps pivoted to said extensions arranged to engage opposite sides of said front wall. 100
7. In a washing machine adapted to be mounted on stationary laundry trays, a frame adapted to overlie the central wall of the trays, means for securing the frame to the trays, a motor carried by said frame and arranged with its axis parallel to the plane of said wall, a casing secured to said frame, an arm secured to and entirely supported by said casing and extending into one of said trays, an impeller disposed in said tray, impeller driving means mounted in said arm, and means connecting the impeller and said driving means. 110
8. In a washing machine adapted to be mounted on a stationary laundry tray having an intermediate partition, a frame, extensions on said frame overlying the front wall of the tray, clamps on said extensions adapted to engage said front wall and a clamp on the frame adapted to engage the intermediate partition of the tray. 125
9. In a washing machine adapted to be 130

45 mounted on an open laundry tray, a casing adapted to be positioned adjacent a wall of the tray, a member extending outwardly from said casing to overlie the interior of said tray, impeller driving means carried by said member, an impeller operatively connected to said driving means and disposed below said member, and means for adjusting the position of said impeller horizontally 10 with respect to the front and rear walls of said tray.

10. In a washing machine adapted to be mounted on a stationary laundry tray, comprising a casing, means for fixedly securing the casing to the tray, an arm extending horizontally from the casing, an impeller arranged below said arm, impeller driving means carried by said arm and means capable of unlimited manual movement vertically 15 with respect to the impeller and driving means and operatively connecting the impeller and said driving means.

11. In a washing machine adapted to be mounted on a stationary tray, a casing adapted to be positioned over a wall of the tray, a cantilever arm extending from the casing, an impeller arranged below said arm, impeller driving means carried by said arm and means connecting the impeller and the driving means.

12. In a washing machine adapted to be mounted upon a receptacle, a casing mounted in proximity to one side wall of said receptacle, power transmission means disposed in said casing, a motor having a shaft operatively connected with said power transmission means, a hollow member extending outwardly from said casing over the interior of said receptacle and below said motor shaft, impeller means journaled in said member at a point remote from said casing, and means carried by said member for operatively connecting said power transmission means with said impeller means.

45 13. In a washing machine adapted to be mounted on a stationary tray, a casing adapted to be positioned over a wall of the tray, a horizontally adjustable cantilever arm extending horizontally from the casing into the tray, an impeller arranged in the tray below the arm, impeller driving means carried by the arm and means connecting the impeller and the driving means.

14. In a washing machine adapted to be mounted on a stationary tray, a casing adapted to be positioned over a wall of the tray, a hollow cantilever arm extending laterally from the casing over the interior of the tray, impeller driving means enclosed in the arm, and an impeller connected to the driving means and disposed below the arm, said arm being adjustable in a horizontal plane to position the impeller in the tray.

15. In a washing machine adapted to be mounted on a stationary tray, a casing adapt-

ed to be positioned over a wall of the tray, a hollow cantilever arm rotatably attached to the casing to permit adjustment of the arm in a horizontal plane, means for securing the arm to the casing to hold it in horizontally 70 adjusted position, impeller driving means enclosed within the arm and an impeller connected to said driving means and disposed below the arm.

16. In a washing machine, a frame, a motor mounted on said frame and having a shaft, a casing secured to the frame and into which the motor shaft extends, a vertically disposed drive shaft in said casing connected to the motor shaft, said casing having 80 a circular lower end concentric with the drive shaft, a hollow arm having a circular opening therein engaging the circular casing end, whereby the arm is rotatable about the axis of the drive shaft, a vertically disposed impeller shaft arranged at the outer end of the arm and driving means 85 enclosed in the arm and connecting the drive shaft with the impeller shaft.

17. In a washing machine adapted to be disposed upon an open laundry tray having an intermediate partition, a frame secured to one side wall and overlying said partition so as to offer substantially no obstruction 90 to the opening in said tray, a member carried by and extending outwardly from said frame and overlying the interior of said tray, vertical impeller means journaled in said member at a point remote from said frame, a motor carried by said frame, and driving 95 means operatively connecting said motor with said impeller means.

18. In a washing machine, a frame, means for detachably mounting the frame upon the side wall of a receptacle adjacent one side 105 thereof so as to offer substantially no obstruction to the opening in said receptacle, a hollow member extending from and having one of its ends supported by said frame, said member overlying the interior of said 110 receptacle, an oscillating impeller rod extending downwardly from said member into said receptacle at a point remote from said frame, impeller drive means carried within said member, a motor carried by said frame, 115 and means operatively connecting said motor with said impeller drive means.

19. In a washing machine, a frame, means for mounting the frame upon a wall of a laundry tray so as to offer substantially unobstructed access to the interior of said tray, a motor carried by said frame, an upstanding casing also carried by said frame, a member extending over the interior of said receptacle and having one of its ends connected to said casing at a point below said motor, impeller means extending downwardly from said member into the interior of said tray, drive means carried by said member, and interconnecting means extending down- 125 130

wardly in said casing and operatively connecting said motor with said driving means.

20. In a washing machine adapted to be mounted on an open laundry tray having an intermediate partition, a frame overlying said central partition and having one of its ends supported by an adjoining side wall, clamping means adjacent said end of said frame for clamping the same to said side wall of said tray, and means bearing upon said intermediate partition for supporting the other end of said frame.

21. In a washing machine, a receptacle, a frame secured to said receptacle, motor means supported by said frame, a member overlying the interior of said receptacle, a vertical shaft journaled in said member and

having a non-circular bore, means for operatively connecting said shaft and motor means whereby movement is imparted to said shaft, 20 an impeller positioned beneath said member and adapted to be supported by the bottom of the receptacle, said impeller having a non-circular bore, and a rod operatively connecting said shaft and impeller, said rod being 25 slideable longitudinally with respect to both bores whereby the rod may be manually lifted during movement of said vertical shaft to disengage said impeller.

In testimony whereof, we have hereunto 30 set our hands.

FRANK B. MOREHOUSE.
FRANK HAASE.
